SEWING MACHINE

Charles W. Mueller, St. Louis, Mo., assignor to
 Lewis Invisible Stitch Machine Company, St.
 Louis, Mo., a corporation of Maine

Application January 29, 1937, Serial No. 123,059

5 Claims. (Cl. 112—176)

This invention relates to new and useful improvements in sewing machines generally, although more particularly to a blind stitch sewing machine of the post type such as is shown in my prior Patents 2,038,848 and 2,038,849 issued Apr. 28, 1936, and in my co-pending application Serial No. 127,983, filed Feb. 26, 1937, for improvements in Sewing machines.

In said patents and application, the base arm 10 extends laterally from the standard and thence forwardly to the post, and consequently when the machine is set on a bench the laterally extending portion of the base arm precludes the sewing of small articles, such as infants' dresses, etc.

15 The principal object of the present invention is to provide a main frame wherein the base arm extends forwardly and thence laterally to the post thereby permitting the bench to be cut away in rear of the post to provide the necessary clearance when sewing infants' dresses and other small articles.

20 With the above and other objects in view which will more fully appear, the nature of the invention will be more clearly understood by following the description, the appended claims, and the several views illustrated in the accompanying drawings.

In the drawings:—

25 Figure 1 is a top plan view of a sewing machine constructed in accordance with my invention.

Figure 2 is a left end elevation thereof, the post housing being shown in section.

Figure 3 is a horizontal section taken on the line 3—3 of Figure 2.

Figure 4 is a vertical section taken through the standard and forwardly extending base arm, and

Figure 5 is a vertical section taken through the 40 post.

Like reference numerals designate corresponding parts throughout the several figures of the drawings.

By reference to the accompanying drawings, 45 it will be seen that my invention includes a main frame A which comprises a standard 5 having an upper horizontal arm 6 extending laterally from the upper end thereof and terminating in a forwardly extending upper arm 7, and a base arm 8 which extends forwardly from the lower end of the standard and terminates in a laterally extending arm 9 disposed in front of and in parallel relation to the upper arm 6, the free end of the base arm 9 being disposed below the free 55 end of the upper arm 7.

Rigidly fixed to the free end of the upper arm 7, is a horizontal presser foot B having a centrally located opening.

Journalized in the upper end of the standard 5 and in the upper arm 6 is a main shaft 11. Journalized in the upper arm 7 and extending longitudinally thereof is an oscillatory needle shaft 12 having a needle arm 13 fixed to its front end. Attached to the needle arm 13 is a curved needle 14 which reciprocates across said opening of the foot. The needle shaft 12 is oscillated from the main shaft 11 by the usual connections. A looper or spreader 15 cooperates with the needle 14 in the usual manner to form single thread chain stitches, although any other type of complementary stitch forming mechanism may be employed if desired.

20 Located directly under the presser foot B and movable upwardly towards the foot and downwardly therefrom, is a work supporting post C. The post C is rectangular in horizontal cross section and is mounted in a 2-part well or housing D, the right hand part or wall 16 being rigid with and projecting upwardly from the forward end of the base arm 9, and the left hand part or wall 17 constituting a removable cover for the post and certain movable parts which are located therein. The upper edge of the housing D is located below and in spaced relation to the presser foot B, and the upper portion of the post C projects upwardly above said upper edge. The walls 16, 17 of the housing are conjointly formed with an opening to freely receive the post C. The post C is guided in its vertical movements by front and rear vertical guide bars 18, 19.

25 Carried by the post C and bodily movable up and down therewith are a work clamp E and a ridge-forming element F.

The ridge forming element F which projects nodes of material upwardly through the slot of 40 the presser foot into needle penetrating position, comprises a stepped disc which is fixed to a transverse rock shaft 20 journalized in the post C whereby the disc may be oscillated forwardly and rearwardly. The axis of the disc i. e., the shaft 20, is 45 located below and in parallelism with the path of movement of the needle 14, or in other words, at right angles to the line of feed. It will be also observed that the disc is located directly below the needle shaft 12, and in register with the opening of the presser foot B, and is adapted to project intermittently nodes of material upwardly through said opening into needle penetrating position.

50 The disc is reciprocated from the main shaft 11 55

by a train of mechanism which includes a reduction gear coupling **X** which is mounted in the standard **5** and is fully disclosed in my prior Patent 2,038,849 and in my co-pending application referred to above. A rock shaft **21** is journaled in the rear end of the base arm **8** directly below the standard **5**, and a bell crank lever having a horizontal arm **22** and a vertical arm **23** is fixed to said shaft. A pitman **24** has its upper end 5 operatively connected to the reduction gear coupling **X** and its lower end pivotally connected to the horizontal arm **22**. A rock shaft **25** extends longitudinally within the base arm **9** and is provided at its right hand end with an upstanding rock arm **26** which is connected by a link **27** to the vertical arm **23**. The left hand end of the rock shaft **25** is located in rear of the post **C** and is provided with a rock arm **28**. A vertically disposed lever **29** is fulcrumed intermediate its ends on the post **C** and a link **30** connects the rock arm **28** with the lower end of said lever. The upper end of said lever is connected by a link **31** to the disc **F**. Thus it will be seen that the disc is reciprocated from the main shaft **11** by a train of mechanism which includes the rock shaft **25** which extends longitudinally within the base arm **9** and a driving link **27** therefor which extends along and within the base arm **8**.

It is desirable to provide means for depressing the post **C** for the purpose of inserting work under the foot or withdrawing work therefrom. The post is provided with a depending lug **32** and a toggle is interposed between and connected to the lug and to the base arm **9**. This toggle includes a bell crank lever **33** which includes a substantially vertical arm **34** and a forwardly extending and substantially horizontal arm **35**. The lower end of the arm **34** is fulcrumed on an eccentric **36** which is fixed to a horizontal shaft **37** which extends across the well **D** and below the post **C**. The shaft **37** extends longitudinally of the base arm **9** and its right hand end projects into the base arm **8**. A normally vertically disposed link **38** is pivotally connected at its upper end by a pin **39** to the lug **32** and at its lower end by a pin **40** to the upper end of the toggle lever arm **34**, the pin **40** being rigidly secured to the link **38** by a set screw **41**. A coil spring **42** is disposed around the projecting end of the pin **40**, one end of the spring being anchored in a transverse slot **43** formed in the end of the pin and the other end of the spring engaging under a stop pin **44** fixed to the bell crank lever **33**. The spring **42** functions to yieldably retain the toggle elements **34, 38** in their vertical or locked positions. A chain **45** adapted to be connected to a treadle or knee-press, has its upper end connected to the outer end of the horizontal arm **35** of said bell 55 crank lever. Thus, upon operation of the knee-press or treadle the toggle will be broken and the post **C** together with the parts mounted thereon, will be depressed to permit the ready insertion or withdrawal of the material, and upon release of said knee-press or treadle the parts will be returned to their normal position by the spring **42**.

In order to positively adjust the normal vertical position of the post **C** and thereby set the machine for materials of different thicknesses, I have provided a hand adjusting shaft **46** which is journaled in a bushing **47** mounted in a tubular bearing bracket **48** secured in an opening **49** formed in the front wall **50** of the standard **5**. A finger knob **51** is rigidly attached to the front end of the

shaft **46** and is provided with a series of rearwardly projecting teeth **52** arranged concentrically thereon for engagement with a spring pin **53** mounted in the bearing bracket **48**. A pointer **54** is fixed to the bracket **48** and overhangs the knob **51** for cooperation with a series of numerals **55** arranged sequentially on the front face of the knob. The inner end of the bracket **48** is provided with a pair of arms **56, 56** in which is fixed a horizontal bearing pin **57** on which is journaled a worm wheel **58** which is in constant mesh with a worm formed on the inner end of the shaft **46** as shown in Figure 4.

A bell crank lever having a horizontal arm **59** and a vertical arm **60** is fulcrumed on a stub shaft **61** mounted in the rear end of the base arm **8** below the standard **5**, the arm **59** being connected by a link **62** with the worm wheel **58**. A pinion **63** is fixed to the right hand end of the shaft **37** and a rack bar **64** extends longitudinally with the base arm **8** and has its rear end pivotally connected to said vertical arm **60**. The front end of the rack bar is disposed below the pinion and is provided with rack teeth **65** which engage the teeth of said pinion. A disc **66** is journaled on the shaft **37** and carries a pin **67** which forms a support for the front end of the rack bar. A coil spring **68** has one end connected to a pin **69** mounted on the disc and its other end to a pin **70** mounted on the base arm **8**. The disc **66** is in the nature of a lever and the spring **68** exerts a pull on the lever to maintain the rack bar in yieldable engagement with the pinion. Thus when the knob **51** is rotated, the rack bar **64** will be moved endwise, the shaft **37** together with the eccentric **36** will be rotated, and the post **C** will be raised or lowered, depending on the direction of rotation of the knob. It will therefore be seen that the post adjusting means includes a hand control element mounted on the standard **5**, a horizontal shaft **37** which extends longitudinally within the base arms **8** and **9**, and a rack bar **64** which extends longitudinally within the base arm **8**.

It is of course to be understood that the details of structure and arrangement of parts may be variously changed and modified without departing from the spirit and scope of my invention.

I claim:

1. In a blind stitch sewing machine, a main frame comprising a standard having an upper arm extending laterally therefrom and terminating in a forwardly extending arm, and a base arm extending forwardly from the standard and cooperating with the latter to support the frame and terminating in a laterally extending arm arranged in front of and in parallelism with the laterally extending upper arm, blind stitch forming means including a horizontally reciprocable needle supported on the forwardly extended arm and a movable ridge forming element mounted on the base arm, the free end of the base arm being disposed substantially under the free end of the upper arm.

2. In a blind stitch sewing machine, the combination with a main frame comprising a standard having an upper arm extending laterally therefrom and terminating in a forwardly extending arm, and a base arm extending forwardly from the standard and cooperating with the latter to support the frame and terminating in a laterally extending arm arranged in front of and in parallelism with the laterally extending upper arm, the free end of the base arm be-

ing disposed substantially under the free end of the upper arm, of a horizontal presser foot fixed to the free end of the upper arm, a main shaft journaled in the standard, a stitch forming mechanism including a horizontally reciprocating needle mounted on the free end of the upper arm above the foot and having driving connections with the main shaft, a post mounted on the free end of the base arm directly below the foot, a movable ridge forming element mounted on the post for projecting a ridge of material upwardly through the foot into needle penetrating position, and driving connections between the ridge forming element and the main shaft and extending along the base arm and into the standard.

3. In a blind stitch sewing machine, the combination with a main frame comprising a standard having an upper arm extending laterally therefrom and terminating in a forwardly extending arm, and a base arm extending forwardly from the standard and cooperating with the latter to support the frame and terminating in a laterally extending arm arranged in front of and in parallelism with the laterally extending upper arm, the free end of the base arm being disposed substantially under the free end of the upper arm, of a horizontal presser foot fixed to the free end of the upper arm, a main shaft journaled in the standard, a stitch forming mechanism including a horizontally reciprocating needle mounted on the free end of the upper arm above the foot and having driving connections with the main shaft, a post mounted on the free end of the base arm directly below the foot, a movable ridge forming element mounted on the post for projecting a ridge of material upwardly through the foot into needle penetrating position, and driving connections between the ridge forming element and the main shaft comprising a rock shaft extending longitudinally within the laterally extending base arm and operatively connected with said ridge forming element, and operating connections between said rock arm and the main shaft including a link extending longitudinally within the forwardly extending base arm.

4. In a blind stitch sewing machine, the combination with a main frame consisting a stand-

ard having an upper arm extending laterally therefrom and terminating in a forwardly extending arm, and a base arm extending forwardly from the standard and terminating in a laterally extending arm arranged in front of and in parallelism with the laterally extending upper arm, the free end of the base arm being disposed substantially under the free end of the upper arm, of a horizontal presser foot fixed to the free end of the upper arm, a post mounted for vertical movements on the free end of the base arm directly below the foot, and means for raising and lowering the post including a rotatable shaft extending longitudinally within the laterally extending base arm, a manually operable means mounted on the standard, and operating connections between the shaft and the manually operable means including a pinion fixed to the shaft and a rack bar engageable with the pinion and extending longitudinally within the forwardly extending base arm.

5. In a blind stitch sewing machine, the combination with a main frame comprising a standard having an upper arm extending laterally therefrom and terminating in a forwardly extending arm, and a base arm extending forwardly from the standard and terminating in a laterally extending arm arranged in front of and in parallelism with the laterally extending upper arm, the free end of the base arm being disposed substantially under the free end of the upper arm, of a horizontal presser foot fixed to the free end of the upper arm, a post mounted for vertical movements on the free end of the base arm directly below the foot, and means for raising and lowering the post including a rotatable shaft extending longitudinally within the laterally extending base arm, one end of the shaft being disposed directly under the post, an eccentric fixed to said end of the shaft and having operative connections with the post, a manually operable means mounted on the standard, and operating connections between the shaft and the manually operable means including a pinion fixed to the shaft and a rack bar engageable with the pinion and extending longitudinally within the forwardly extending base arm.

CHARLES W. MUELLER.
